CLAIM

The ornamental design for a shoe outsole bottom as shown and described.

DESCRIPTION

FIG. 1 is a front perspective view of the shoe outsole bottom in accordance with my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

Broken lines shown in the drawing represent environmental structure of the shoe and portions of the shoe outsole bottom that form no part of the claimed design.

1 Claim, 8 Drawing Sheets
